WINDOW SASH CONTROL

Forrest D. Grim, Allentown, Pa.

Application June 4, 1946, Serial No. 674,201

7 Claims. (Cl. 292—74)

1

This invention relates to a mechanism for controlling the upward or downward movement of one member lengthwise with respect to another member in approximately abutting relationship.

The mechanism is particularly useful as a window sash control and will first be illustrated by description in connection with such use.

Many different kinds of stops for window sash have been proposed and successfully used. There has not been developed, however, any small and easily inserted device so satisfactory as to replace largely the weight and cord method of counterbalancing windows which, although requiring a hollow frame, is still the construction preferred in homes and offices.

My invention provides a control device that makes possible stopping a window sash at any desired elevation, holds the sash in that position until forced from it by hand or like pressure and makes unnecessary the use of a weight and cord to counterbalance the weight of the sash.

Briefly stated, my invention comprises the herein described control device comprising a plate member that is preferably of generally flat face, a roller disposed behind the plate member, and spring actuated means forcing the roller against the back of the said member so as to insure adequate friction of the face of the plate member against an approximately abutting element such as the upright side of the frame within which there is mounted the article, the movement of which is to be controlled. In the preferred embodiment, the invention comprises means for mounting the said roller within a slot which is inclined toward the face of the plate member and means, as, for example, a spring, tending to force the roller at all times toward that portion of the slot which is nearest to the plate member, so as to make certain that the roller at all times applies controlled pressure against the back of the plate member and yet permits the plate member to accommodate itself to irregularities of surface of the said frame against which bears the face of the plate.

The invention will be illustrated in greater detail by description in connection with the attached drawing to which reference is made.

Fig. 1 is a perspective view of a structure embodying my invention, the structure being partly broken away for clearness of illustration.

2

Fig. 2 is a horizontal section of a modified form of structure embodying the invention.

Fig. 3 is a sectional view of the sash control device.

5 Fig. 4 is a sectional view on line 4—4 of Fig. 3.

Fig. 5 is an exploded perspective view of the sash control mechanism.

The mechanism includes a member of flat face 10 serving in use to engage the frame 29 in which moves the article to be supported, the said member being suitably generally U-shaped and having sides 12.

Disposed behind the yoke is roller 14 with cylindrical extension 16 to constitute bearings.

15 The mechanism includes a housing provided with a depression to receive the operating parts, the housing having a back 18, ends 20, flanges 22 extending from the forward edges of the depressed portion and at approximately right angles to the said ends and provided with holes 24 to receive fastening members such as the screws 26 for holding the device to the window sash 28 or other object, the movement of which within the window frame 29 is to be controlled.

20 25 The housing includes also the sides 30 provided with slots 32 (Fig. 5) which are inclined from the vertical when the apparatus is in operating condition so that at one end the slots are nearer to the plane of the frame 29, that is, to the face 30 of the yoke member than at the other end.

These sides 30 provided each with a slot of the kind described are spaced from each other at such a distance as to receive the roller bearings 16 and provide mountings therefor.

30 35 Flanges 31 extend inwardly from the forward edges of the sides 30, so as to engage shoulders on the sides 12 of the yoke member and thus avoid accidental disengagement of the yoke member from the housing.

40 45 A roller actuating member indicated generally at 34 is generally channel-shaped with sides 36 extending at approximately a right angle to the plane of the face 10 and being provided with cut outs 38, the sides being so spaced that the cut-outs receive the cylindrical extensions 16 of the roller just inside the sides 30.

Spring 40 is secured in any convenient manner to the actuating member as by pin 42 and at the other end to the housing in any convenient manner, as to the tab with eyelet at 44. The spring is

of such dimension that it is under tension and, for that reason, tends to draw the actuating member in direction towards the part of slots 32 nearest the face 10, that is, towards the top in Fig. 3, so that the roller 14 is at all times forced by this spring action against the back of the yoke member, face 10 of which engages the frame 29 or other part with respect to which the movement of the window 28 is to be stopped.

For making the spring accessible, there is provided opening 46 in the back of the housing (Figs. 4 and 5).

The operation of the mechanism will be largely evident from the description of it that has been given.

When the window to be supported is moved upwardly or downwardly, the face 10 of the plate engaging member slides by friction over the surface of the approximately abutting part 29 representing, for instance, the inside of the frame for a 2-sash window. As the face 10 moves over irregularities of surface of the frame, that is, over parts spaced unevenly from the edge of the sash 28, the roller is free to move within the slots 30 so as to offset variations in the spacing between elements 28 and 29. At all times, however, the spring tension forces the roller outwardly against the yoke of face 10, with a firmness that is controlled by tension on the spring 40.

The inclination of the slots 32 gives to the spring action a mechanical advantage analogous to that of an inclined plane, so that an exceptionally strong spring is not required to give sufficient pressure of the roller against the face 10 of the yoke.

When the position of article 28 is to be allowed to remain fixed with respect to the approximately abutting member or framework 29, then hand or other external pressure is no longer applied. Under such conditions, the engagement of face 10 against the abutting members such as the upright frame part 29 suffices to hold article 28 in position. Any movement of 10 with respect to 29 must overcome the frictional engagement actuated by spring 40 through roller 14.

The device may be used with objects of widely varying weight, the force of the spring being varied in accordance with the weight or difficulties of support otherwise introduced. Also the slope of the slots 32 with respect to the plane of face 10 may be varied, the greater mechanical advantage in the spring action being obtained with a relatively flat slope of slots 32 with respect to the face 10.

Materials of construction are those that are usual in parts of the class illustrated. I prefer to make the housing, roller, and all parts of the mechanism of iron, steel or alloys thereof, brass, or aluminum. The spring 40 is of conventional construction, suitably of spring steel.

In the modification shown in Fig. 2, the control mechanism of the kind described is inserted into the window frame 29. One of the mechanisms is inserted into the channel of the frame which receives one of the sashes of a usual window with upper and lower sashes and the other mechanism in the channel to receive the other of the said sashes. In this construction the face 10 of the yoke member contacts the edge of the window sash instead of the edge of the window frame as described previously. Otherwise the mounting and operation is the same as described.

My control mechanism is small in overall size, simple in construction and effective and convenient in operation.

While the mechanism has been illustrated in connection with window sash control, it may be used with other objects of conventional type for controlling the movement of an object which at its edges fits slidably between frame members.

It will be understood also that it is intended to cover all changes and modifications of the example of the invention herein chosen for the purpose of illustration which do not constitute departures from the spirit and scope of the invention.

What I claim is:

1. Control mechanism for an article slidably movable alongside an approximately abutting frame, the control mechanism comprising a member having a face frictionally engaging the frame, a roller disposed against the back of the said member, and means forcing the roller against the said member so that the face of the said member is held against the frame.

2. A control device adapted to serve as a stop for the movement of the sash within a window frame, the device comprising a plate of generally flat face, a roller disposed directly behind the plate, a support for the roller having sides spaced to receive the roller therebetween and extending at approximately right angles to the axis of the roller, the said sides being provided each with a slot inclined with respect to the plane of the said face, means mounting the roller rotatably between the said sides and within the slots, and means forcing the roller towards the parts of the said slots nearest to the face of the said plate.

3. The control device described in claim 2, the said means tending to force the roller mountings towards the portion of the slots closest to the said plate being a spring.

4. The control device described in claim 2, the means mounting the roller including extensions from the roller constituting bearings mounted in the slots and the said means tending to force the roller mountings towards the portion of the slots closest to the plate comprising a generally channel shaped element having sides provided with cut-outs to receive the extensions from the roller, the cut outs being oversize with respect to the extensions so as to permit free rotation of the mountings therewithin and spring means forcing the channel element in direction to move the roller mountings towards the portion of the said slots nearest to the said plate which engages the frame.

5. Control mechanism for an article slidably movable alongside an approximately abutting frame, the control mechanism comprising a member mounted movably so that it may be pressed against the frame, a roller disposed behind the said member and having cylindrical extensions

6. constituting bearings, a housing for the roller and said member having sides provided with slots inclined with respect to the said frame, the said bearings being mounted in the slots, and means for forcing the roller at all times against the back of the said member so as to exert pressure thereon in the direction of the frame, the said means including a generally channel-shaped member having flanges extending each at approximately a right angle to the plane of the face of the frame and provided with cut-outs engaging the said bearings, and spring means forcing the channel-shaped member and bearings mounted therein in the direction of the part of the slots nearest to the frame.

7. The control device described in claim 2 the

said plate being in the form of a yoke of generally U-shape, the base of the U being flat and serving to engage frictionally the window frame and the two sides of the U extending inwardly beyond the ends of the roller.

7. The control device described in claim 2 the said plate being in the form of a yoke of generally U-shape, the base of the U being flat and serving to engage frictionally the window frame, the two sides of the U extending inwardly beyond the ends of the roller, and the device comprising a housing including a depressed portion thereof of depth to receive the mechanism described including the said sides of the plate member and

including flanges extending laterally from the forward edges of the depressed portion and serving, when the device is inserted into a sash, to provide points for securing the whole device to the sash.
